UNITED STATES PATENT OFFICE

2,449,903

SECTIONAL DINING TABLE

Robert Langstaff, Donora, Pa.

Application January 20, 1947, Serial No. 723,603

2 Claims. (Cl. 311—1)

1

This invention relates to extension tables.

An object of this invention is to provide a table assembly which can be collapsed to compact form and thereby provide a single table, or other article of furniture such as a sideboard or the like.

Another object of this invention is to provide a table construction wherein a normal table may be formed, or the table may be collapsed to form a coffee table.

Another object of this invention is to provide an extension table construction wherein one part telescopes into another part and the other part includes a movable top which can be raised to provide for the reception of the first part.

A further object of this invention is to provide an extension and collapsible table assembly, including an improved hinge for securing an auxiliary top to an edge of the main top, whereby the auxiliary top may be raised to vertical position above the main top, or may be lowered to a horizontal position substantially coplanar with the main top.

A further object of this invention is to provide a sectional table which in collapsed form will occupy only a small space, and which may be extended to form a large size dining table.

With the above and other objects in view, my invention consists in the arrangement, combination and details of construction disclosed in the drawings and specification, and then more particularly pointed out in the appended claims.

In the drawings, Figure 1 is a detail top plan of an extensible table assembly constructed according to an embodiment of this invention.

Figure 2 is a sectional view taken on the line 2—2 of Figure 1.

Figure 3 is a detail end elevation of one of the table members with the adjustable top thereof in vertical sideboard forming position.

Figure 4 is a detail rear elevation of the table shown in Figure 3.

Figure 5 is a fragmentary sectional view taken on the line 5—5 of Figure 4.

Figure 6 is a detail end elevation of the table member shown in Figures 4 and 5, with the hinged top in depending relation and showing the manner of raising the main top thereof to provide for reception of another table.

Figure 7 is a fragmentary sectional view taken on the line 7—7 of Figure 6.

Figure 8 is a detail end elevation of an intermediate collapsible table.

Figure 8A is a detail end elevation of another one of the intermediate collapsible tables.

Figure 9 is a detail end elevation of the table shown in Figure 8A.

Figure 10 is a fragmentary vertical section showing the manner of holding the legs of the

table shown in Figure 9 in collapsed or lowered position.

Figure 11 is a detail end elevation of the table shown in Figure 8.

Figure 12 is a fragmentary sectional view taken on the line 12—12 of Figure 11.

Figure 13 is a fragmentary sectional view taken on the line 13—13 of Figure 1.

Figure 14 is a fragmentary detail view of another modification of this invention.

Figure 15 is a sectional view taken on the line 15—15 of Figure 14.

Referring to the drawings, the numerals 15, 16, 17 and 18 designate generally a series of tables which in extended position are adapted to form an elongated or large dining room table. The tables 15 to 18 are independently supported and are adapted to be disposed in top edge abutting relation, as shown in Figure 2, so as to provide a long, flat top. The table 15 forms the main table and comprises, as shown particularly in Figures 3 to 6 inclusive, a plurality of legs 19 having secured to the upper ends thereof a rectangular frame 20.

A top 21 is adapted when in lowered position to engage on the upper edge of the frame 20 and legs 19. The top 21 is swingably supported relative to the base which comprises frame 20 and legs 19, by means of pairs of links 22 engaging the opposite ends of the top 21, being pivoted as at 23, to the edges of the top 21 and pivoted as at 24, to the upper portion of the base.

The table 15 also includes a hinged top or plate 25 which is hingedly connected to the base of the table 15 by means of a pair of hinged members generally designated as 26. The hinged members 26, shown more clearly in Figures 4 and 5, include a fixed leaf 27 secured by fastening members 28 to a depending block 29 carried by the table base. The hinge 26 also includes a swingable leaf 30 pivoted to the stationary leaf 27 by means of a pintle 31. The leaf 30 is relatively long and is formed with an elongated slot 32 through which a fastening member 33 loosely engages. The fastening member 33 may be in the form of a screw which is threaded into the plate 25, and a washer 34 may be interposed between the head of the screw 33 and the outer side of the leaf 30.

By means of the sliding hinge structure 26, the plate or top member 25 may be raised to a vertical position and have the lower edge thereof resting on the top of the top member 21, as shown in Figures 3 and 4. The plate 25 may also have a mirror or glass top 35 mounted on the upper side thereof so that the upright plate 25, with the mirror 35, may form a sideboard back wall extending above the top of the table 15.

When it is desired to use the plate or hinged top member 25 as a table top extension, the plate

25 may be disposed in a horizontal position, as shown in Figure 2. The outer or free edge of the plate or hinged top 25 is supported in a horizontal position by means of a leg 36 which is hinged, as at 37, to the lower side of the top or plate member 25.

The table member 18 is preferably a conventional table formed of a base generally designated as 38, which includes legs 39 and a rectangular frame 40 on which a top 41 is secured. The top 41 is disposed in a position where it will be coplanar with the top 15 when the latter is in its lowered position. The top 41 is also supported at such height that when the top 21 of the table 15 is elevated, as shown in full lines in Figure 6, the top 41 may slide over the base of the table 15 after which the top 21 may be lowered to rest, as shown in dotted lines in Figure 6, on top of the top member 41.

The table member 16, shown in greater detail in Figures 8 and 11, is formed of a base generally designated as 42, which includes a rectangular frame 43 having a flat top 44 secured thereto. The frame 43 has pivotally secured thereto opposed pairs of legs 45 and 46. The legs 45 are pivoted on pivot members 47 and engage within the inner sides of the frame 43 so that when the table 16 is in collapsed position the legs 45 will engage the lower edge of the frame 43. The legs 46 are pivoted on fastening members 48 and are mounted on the outer sides or ends of the frame 43. A stop member 49 is associated with each leg 46, being secured in outstanding relation on the frame 43 so that the lower ends of the legs 45 and 46 will be coplanar when these legs are in collapsed position, as shown in Figure 11.

Preferably the fastening members 47 and 48 are in the form of bolts, having wing nuts 50 threaded thereon so that the legs 45 and 46 may be securely tightened when the table is in its extended position, and the legs are vertical. The top 16 may be constructed in the form of a plate 51 formed with a recess 52 within which a transparent panel 53 is adapted to be secured by corner plates 54.

The table 17 is constructed somewhat similar to the table 16 and includes a top 55 secured to a rectangular frame 56. The frame 56 has pivotally secured thereto pairs of collapsible legs 57 and 58. The legs 57 are adapted to engage on the inner side of the frame 56, being mounted at their upper ends on bolts 59 and these legs held in collapsed position by means of stop blocks 60 secured to the inner side of the frame 56. The legs 59 are adjustably mounted on bolts 61, having wing nuts 62 threaded thereon and these legs 58 engage on the outer side of the frame 56. The legs 58 are limited in their pivoting to collapsed position by means of a stop block 63 which is secured in a suitable manner to the outer side of the frame 56.

Preferably the table 17 is designed so that it will be at a slightly greater height when in collapsed position than the table 16. The tables 16 and 17, when in collapsed or lowered position, may be used as coffee tables or other low height tables. When it is desired to form a long dining room table, the main or base table 15 has the extensible top member 25 swung outwardly to horizontal position and supported by means of the leg 36. The table 18 is pulled from beneath the movable top 21 and the small tables 16 and 17 are raised to their extended height wherein the tops thereof will be coplanar with the lowered top

21 of table 15. The extended tables 16 and 17 may then be interposed, as shown in Figure 1, between table 15 and table 18. These tables 16 and 17 have a width such that when their lengthwise edges are in abutting relation they will have a combined width equal to the length of the tables 15 and 18.

In Figures 14 and 15, there is shown a modified form of this invention wherein the legs of the table may be collapsed to lower the height of the table. Each leg is formed of upper and lower leg members 65 and 66 respectively, which are hinged together as at 67. The lower leg member 66 has a locking plate 68 pivotally secured thereto and formed with a notch 69 through which a locking bolt 70 extends. A wing nut 71 is threaded onto bolt 70 for locking the lower leg member 66 in aligned position with respect to the upper leg member 65. When lower leg member 66 is in collapsed position, as shown in dotted lines in Figure 14, plate 68 may be swung upwardly to the dotted position shown in Figure 14.

With a table construction as hereinbefore described, a great deal of space will be conserved, particularly when the table is in its collapsed form. These individual tables may be used separately from the main table, but when it is desired to form a long table they may be disposed in abutting relation, as shown in Figure 2.

I do not mean to confine myself to the exact details of construction herein disclosed, but claim all variations falling within the purview of the appended claims.

What I claim is:

1. An extension table comprising a pair of table members, each formed of a top and a base, one of said members including link means connecting the top thereof to the base whereby said top may be elevated above the base, the other table member being of such size and shape that it may be shifted into the base of said one member with the top thereof interposed between the base of said one member and the top of the latter.
2. A combination sectional dining table of the kind described comprising a plurality of table members, a top, legs and a base on each of said members, link means connecting the top to the base of at least one of said members whereby the top may be raised above the base, the top of another one of said table members being of such size and shape that it may be positioned between the base and raised top of said one table member.

ROBERT LANGSTAFF.
